A. H. STEBBINS

SCREEN

Filed March 6, 1925

Fig. 1

INVENTOR:
Albert H. Stettinius,
BY Robert H. Hains.
ATTORNEY

UNITED STATES PATENT OFFICE.

ALBERT H. STEBBINS, OF LOS ANGELES, CALIFORNIA.

SCREEN.

Application filed March 6, 1925. Serial No. 13,442.

To all whom it may concern:

Be it known that I, ALBERT H. STEBBINS, a citizen of the United States, residing at Los Angeles, in the county of Los Angeles and State of California, have invented an Improvement in Screens, of which the following description, in connection with the accompanying drawings, is a specification, like characters on the drawings representing like parts.

This invention relates to screens and more particularly to means for removing dust laden air from a closed screen casing.

In screening materials that produce considerable dust, it is desirable to perform the screening operation within a completely closed casing. The dust laden air confined within the screening casing tends to squeeze out into the discharge bins and through other openings in the casing, which is objectionable.

The present invention therefore relates to means for removing the dust laden air from the screen casing, and the construction is such that it serves also to classify the lighter materials picked up by the air.

The novel features of the invention and combination of parts will be hereinafter described in connection with the accompanying drawings, which illustrate one good, practical form thereof.

In the drawings:—

Fig. 1 is a side elevation with parts in section of a vibratory screen embodying the present invention.

Fig. 2 is a sectional view taken on the line 2—2 of Fig. 1; and

Fig. 3 is an enlarged sectional view of a portion of the operating shaft and one of the operating sheaves.

The present invention may be employed with any type of screen that is provided with a closed casing, and in the present case is shown as applied to a vibratory screen of the inclined type.

The screen casing may be variously constructed and as shown is provided with the side walls 10 secured to the cover 11 and floor 12, and the casing may be strengthened by longitudinally extending beams 13 secured to the side walls. The screen casing may be provided with one or more screening surfaces and is shown as having an upper screening surface 14 and a lower screening surface 15 secured to the side walls 10. The materials to be treated are delivered to

the upper screen by one or more hoppers 16. The larger particles that fail to pass through the upper screen are discharged through the chute 17, while the particles that do not pass through the lower screen are discharged through the chute 18, and the fine particles that fall upon the floor 12 are discharged through the chute 19.

The screen shown is supported to slope in the direction of its length, and is mounted upon a frame formed of side beams 20 connected by transverse braces 21. The lower end of this frame is pivotally secured to base timbers 22 at 23 and the upper end of the frame is supported by uprights 24 secured to the timbers 22 and having the slotted braces 25 adjustably secured to the uprights by bolts 26.

Various means may be provided for supporting the screen for vibratory movement and for vibrating the same, and in the construction shown the screen casing is yieldingly mounted upon the supporting frame by coiled springs 27 seated upon the frame 80 and the upper ends of which rest against the transversely extending braces 28 of the screen casing. The means shown for imparting a vibratory movement to the screen casing consists of cables 29 at each side of the casing and one end of each cable is secured to the casing by a clamp 30, while the opposite end of each cable is fastened to the frame at 31. The intermediate portion of each cable passes around a grooved sheave 32 operated by eccentrics 33 upon the transversely extending shaft 34 that is rotatably mounted in bearings 35. The eccentrics 33 are rotatably mounted within the sheaves 32, and rollers or other anti-friction bearings 36 are provided between the eccentrics and sheaves. The arrangement is such that as the shaft 34 is rotated it moves the sheaves 32 to and from the cable tightening position, thus pulling the screen casing slightly in an upward direction and then releasing it to move downwardly under the force of gravity.

The mechanism so far described may be of well known or any preferred construction and is illustrated and described to make clear the application of the present invention to a closed screen casing. The means of the present invention for removing dust laden air from the casing will now be described, and to this end a conduit is provided within the screen casing below the

screening surface 15 and has an open end through which air is drawn from the casing into the conduit. The conduit is conveniently formed by providing a partition 37 within the casing which extends downward from the upper end of the casing a substantial distance between the floor 12 and screening surface 15. Air is exhausted from the chamber 38 formed between the partition and floor by a pipe 39 which may be connected to a suction fan. The chamber 38 is made relatively large and of substantial length so that the heavier particles carried upwardly by the air will have an opportunity to settle therein and slide down the floor of this chamber.

It is desirable to provide a door within the chamber 38 to control the passage of air therethrough, and in the construction shown this is accomplished by providing the swinging trap 40 pivotally supported at 41 and arranged to restrict the air passage, the arrangement being such that the trap is free to swing upwardly sufficient to allow the particles that are carried upwardly by the air and lodge back of the trap to escape. The restricted air passage formed by the trap 40 may be varied in size by adjusting the door 42 pivotally mounted at 41 and which is urged upwardly by springs 43. The door 42 is held open the desired amount by bolts 44 having adjustable nuts upon their outer ends.

It may be desirable to admit air into the screen casing at one or more points and to this end the air inlet openings 45 are provided the size of which may be adjusted by adjusting the bolts 46.

From the foregoing it will be seen that the dust laden air within the screen casing will travel in the directions indicated by the arrows toward the entrance to the chamber 37 and then up this chamber. The restricted passage formed in this chamber by the trap 40 serves to retard the flow of air therein; this gives the heavier particles a chance to settle therein and slide down the floor 12 to the exit 19. The eccentric shaft 34 may be driven from an operating shaft 47 by the belt 48.

What is claimed is:

1. In a screen, in combination, a closed casing supported at an inclination in the direction of its length, a partition in the casing below the screening surface and extending from the upper end of the casing lengthwise thereof a substantial distance to provide an air chamber below the partition, and means for exhausting air from the upper end of said chamber to draw the dust laden air within the casing upward through said chamber in opposition to the force of gravity to cause the heavier particles carried upwardly by the air to settle in the chamber and slide downwardly therein.

2. In a screen, in combination, a closed casing supported at an inclination in the direction of its length, a screening surface within the casing, a partition mounted in the casing below the screening surface and extending from the upper end of the casing lengthwise thereof a substantial distance to provide an air chamber below the partition, means at the upper end of the air chamber for exhausting air from said chamber to draw the dust laden air within the casing upward through said chamber so that the heavier particles carried upwardly by the air may settle in the chamber, and an adjustable door to control the passage of air from said chamber.

3. In a screen, in combination, a closed casing supported at an inclination in the direction of its length, a screening surface within the casing, a partition mounted in the casing below the screening surface and extending from the upper end of the casing lengthwise thereof a substantial distance in spaced relation to the casing floor so that the materials that pass through the screening surface fall upon the partition and are excluded thereby from the chamber formed between the partition and floor, and means at the upper end of said chamber for exhausting air from the chamber to draw the dust laden air within the casing into said chamber at the lower end of the partition and upwardly within the chamber to promote settling of the heavier particles carried upwardly by the air.

4. In a screen, in combination, a closed casing supported at an inclination in the direction of its length, a screening surface within the casing, an air conduit extending longitudinally within the casing below the screening surface and open at its lower end, means for exhausting air from said conduit to draw the dust laden air within the casing upwardly through the conduit, and a trap door mounted in the conduit to form a restricted air passage therein and movable to release the particles of materials picked up by the air and that lodge behind the trap door.

5. In a screen, in combination, a closed casing supported at an inclination in the direction of its length, a screening surface within the casing, a relatively long air conduit extending longitudinally within the casing below the screening surface and open at its lower end, and means for drawing air upwardly through said conduit to remove dust laden air from said casing so that the air is caused to travel a substantial distance in an upward direction within the conduit and the heavier particles are afforded an opportunity to settle in the conduit and slide downwardly therein.

6. In a screen, in combination, a closed casing supported at an inclination in the

direction of its length, a screening surface within the casing, a partition mounted in the casing below the screening surface and extending from the upper end of the casing 5 downwardly therein a substantial distance to provide an air chamber below the partition, means at the upper end of the air chamber for exhausting air from said chamber

to draw dust laden air into the lower portion of the casing and upwardly therein, and an 10 inclined plate within said chamber for arresting the heavier particles carried upwardly therein by the air.

In testimony whereof, I have signed my name to this specification.

ALBERT H. STEBBINS.
